[57] **CLAIM**

The ornamental design for a bag holder, as shown and described.

DESCRIPTION

FIG. 1 is a perspective view of a first embodiment of the design in which the lateral positions of the two vertical frames are adjustable to a continuum of positions along the base element;

FIG. 2 is a front view of the embodiment of the design shown in FIG. 1, the rear view being a mirror image thereof; FIG. 3 is a right side view of the embodiment of the design shown in FIG. 1, the left side view being a mirror image thereof;

FIG. 4 is a top view of the embodiment of the design shown in FIG. 1;

FIG. 5 is a bottom view of the embodiment of the design shown in FIG. 1;

FIG. 6 is a perspective view of a second embodiment of the design, in which the lateral positions of the two vertical frames are adjustable to a continuum of positions along the base element, and in which the height of the two vertical frames is telescopically variable;

FIG. 7 is a front view of the embodiment of the design shown in FIG. 6, the rear view being a mirror image thereof;

FIG. 8 is a right side view of the embodiment of the design shown in FIG. 6, the left side view being a mirror image thereof;

FIG. 9 is a top view of the embodiment of the design shown in FIG. 6; and,

FIG. 10 is a bottom view of the embodiment of the design shown in FIG. 6.
